Primary Examiner — Kevin K Rudzinski(74) *Attorney, Agent, or Firm* — Wood Herron & Evans LLP**(57) CLAIM**

The ornamental design for a pillar cushion for a vehicle, as shown and described.

DESCRIPTION

FIG. 1 is a front right perspective view of a pillar cushion for a vehicle according to the present invention.

FIG. 2 is a front left perspective view of the pillar cushion shown in FIG. 1.

FIG. 3 is a rear right perspective view thereof.

FIG. 4 is a rear left perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is bottom view thereof.

The views are described from the perspective of a viewer located inside the vehicle, in the front passenger seat (U.S. vehicles), looking rearwardly along the interior wall.
